UNITED STATES PATENT OFFICE.

FRANK SMITH, OF KANSAS CITY, MISSOURI.

STOVE.

1,142,123.

Specification of Letters Patent.

Patented June 8, 1915.

Application filed December 14, 1914. Serial No. 377,089.

To all whom it may concern:

Be it known that I, FRANK SMITH, a citizen of the United States, residing at Kansas City, in the county of Jackson and State of Missouri, have invented certain new and useful Improvements in Stoves, of which the following is a specification.

My invention relates to improvements in stoves, and more particularly to an attachment to replace the ordinary tops of stoves; and one object is to provide a device of this character having an internal arrangement whereby equal distribution of heat throughout the top of the attachment is had, thereby rendering it especially desirable for laundry, cooking, and heating purposes, and effecting economy of fuel.

A further object is to provide a device of this character having a flat top of larger area than the stove top it replaces, so that it can readily accommodate wash-boilers, flat-irons, cooking utensils, etc.

Other objects of the invention will hereinafter appear, and in order that said invention may be fully understood, reference will now be made to the accompanying drawing, in which:

Figure 1 is a front elevation of a stove provided with my attachment. Fig. 2 is a vertical longitudinal section of the attachment and the upper portion of the stove. Fig. 3 is a vertical cross section of the attachment on line III—III of Fig. 1. Fig. 4 is a plan view of the attachment with its top plate removed. Fig. 5 is an inverted plan view of the top plate of the attachment. Fig. 6 is a plan view of an inner chamber constituting part of the invention.

A designates a stove of ordinary construction with its usual top plate removed.

1 designates my attachment which is substituted for the top plate of the stove.

2 designates an outer chamber of the attachment, consisting of a bottom wall 3 and a surrounding side wall 4, preferably, of elliptical form as disclosed by Fig. 4. The front portion of the side wall 4 has a forwardly extending hopper 5 through which fuel may be fed to the fire-pot of the stove A. The hopper 5 is normally closed by a door 6, operably connected at its upper end to a top plate 7. The rear portion of the side wall 4 has a bay 8, for communication with an outlet 9 in the rear portion of the top plate 7.

10 designates an inner chamber surrounded by a concave inner wall 12, which flares upward to its juncture with a surrounding side wall 11, as disclosed by Fig. 2. The side wall 11 is of substantially the same contour as the side wall 4, from which it is spaced to leave an intervening continuous flue 13, formed by the walls 4 and 11, the bottom wall 3 and the top wall 7. A dead space 12^a is left between the walls 11 and 12, and as it is closed at its ends no draft or circulation of air passes therethrough.

The chambers 2 and 10 are provided at their bottom portions with registering openings 14 and 15, respectively, preferably, of circular form and communicating with the upper open end of the stove A, as disclosed by Fig. 2, for the free upward passage of the products of combustion from said stove.

The inner chamber 10 is provided at its front and rear sides with outlets 16 and 17, respectively, which communicate with opposite sides of the flue 13. The outlet 16, is, preferably, left open at all times, but a valve 18 is provided to close the outlet 17 when desired. The valve 18 is fixed to a pintle 19, journaled in the walls 4 and 11, and provided at its outer end with a handle 20. The valve 18 is reliably held in open or closed position by a coil spring 21, bearing at one end against the handle 20 and at its opposite end against a lug 22 on the wall 4.

The top plate 7 is reliably secured upon the walls 4 and 11 by lugs 23 and bolts 24, the former being suitably secured to the wall 4, while the latter extend through holes 7^a in the top plate 7 and through said lugs 23. The top plate 7 is further held in place upon the walls 4 and 11 by depending ribs 26 and 27 engaging the upper portions of said walls 4 and 11, respectively. The top plate 7 is provided with removable lids 28 and 29 to leave openings for the reception of a wash boiler, or cooking utensils.

The attachment 1 is secured to the top flange B of the stove by two bolts 25, extending through registering holes in said flange B and the walls 3 and 12, as disclosed by Fig. 2. The attachment is centered upon the stove by an annular flange 3^a depending from the bottom wall 3 to engage the inner surface of the flange B. The outlet 9 in the top-plate 7 is surrounded by a collar 30, adapted to receive the lower end of a stove pipe C.

In starting a fire in the stove, the valve 18 is, preferably, left open, so that the products of combustion may pass directly out into the stove pipe C through the outlets 17 and 9. When the fire is well underway the valve 18 is closed, so that the products of combustion after passing upward and heating that portion of the top plate covering the top of the inner chamber 10, will pass out through the outlet 16 and into the flue 13, where it divides and flows in opposite directions through said flue to the outlet 9. Thus it will be seen that the top plate is heated in a uniform manner throughout its area and will quickly heat flat irons, or other domestic utensils placed thereon. When desired one or both lids 28 may be removed to admit of the passage of the lower portion of cooking utensils in the resultant openings, and when it is desired to expose the bottom of a wash boiler directly to the heat in the chamber 10, the lid 29 is also removed.

From the foregoing description it is apparent that I have produced an attachment for stoves which may be manufactured at comparatively low cost and possesses the features of advantage above enumerated, and while I have shown the preferred construction, combination and arrangement of parts, I reserve the right to make such changes as properly fall within the spirit and scope of the claims.

Having thus described my invention, what I claim and desire to secure by Letters Patent, is:

1. A device of the character described, consisting of an outer chamber having a surrounding side wall and a bottom wall with a large opening therein, an inner chamber having a surrounding side wall and an inner wall sloping upward to its juncture with said side wall, said sloping wall having an opening at its lower portion registering with the opening in the bottom wall of the outer chamber, the side wall of the inner chamber being spaced from the side wall of the outer chamber to leave an intervening flue which communicates with two outlets leading from said inner chamber, a valve adapted to close one of said outlets, and a top plate to cover the inner and outer chambers, said top plate having an outlet communicating with the intervening flue.

2. A device of the character described, consisting of an outer chamber having a surrounding side wall and a bottom wall with a large opening therein, an inner chamber having a surrounding side wall and an inner wall flaring upward to its juncture with said side wall, said flaring wall having an opening at its lower portion registering with the opening in the bottom wall of the outer chamber, the side wall of the inner chamber being spaced from the side wall of the outer chamber, to leave an intervening flue which

communicates with an outlet leading from said inner chamber, a top plate to cover the inner and outer chambers, said top plate having an opening therein over the inner chamber and an outlet communicating with the intervening flue, a collar surrounding said outlet, and lids to close the opening over the inner chamber.

3. A device of the character described, consisting of an outer chamber having a surrounding side wall and a bottom wall with a large opening therein, an inner chamber having a surrounding side wall and an inner wall sloping upward to its juncture with said side wall, said sloping wall having an opening at its lower portion registering with the opening in the bottom wall of the outer chamber, the side wall of the inner chamber being spaced from the side wall of the outer chamber to leave an intervening flue which communicates with the outlet leading from said inner chamber, a top plate to cover the inner and outer chambers and provided with an outlet communicating with the intervening flue, ribs depending from said top plate to engage the side walls of the chambers, and lugs projecting from the side wall of the outer chamber and forming means to which the top plate is removably secured.

4. A device of the character described, consisting of an outer chamber having an elliptical surrounding side wall and a bottom wall with a large circular opening therein, an inner chamber having an elliptical surrounding side wall and an inner concave wall sloping upward to its juncture with said side wall, said concave wall having a large circular opening registering with the opening in the bottom wall of the outer chamber, the side wall of the inner chamber being spaced from the side wall of the outer chamber to leave an intervening flue which communicates with an outlet leading from said inner chamber, and a top plate to cover the inner and outer chambers and having an outlet communicating with the intervening flue.

5. In combination with a stove open at its upper end, an outer chamber having a surrounding side wall and a bottom wall with a large opening therein to communicate with the upper portion of the stove, a flange on the bottom plate surrounding the opening therein and adapted to engage the upper portion of the stove, an inner chamber having a surrounding side wall and an inner wall sloping upward to its juncture with said side wall, said sloping wall having an opening at its lower portion registering with the opening in the bottom wall of the outer chamber, the side wall of the inner chamber being spaced from the side wall of the outer chamber to leave an intervening flue which communicates with an outlet leading from said inner chamber, and a top plate to cover

the inner and outer chambers and having an outlet communicating with the intervening flue.

6. In combination with a stove open at its upper end, an outer chamber having a surrounding side wall and a bottom wall with a large opening therein communicating with the open top of the stove, an inner chamber having a surrounding side wall and an inner wall sloping upward to its juncture with said side wall, said sloping wall having an opening at its lower portion registering with the opening in the bottom wall of the outer chamber, means to secure the inner and outer chambers to the stove, a flue between the side walls of the inner and outer chambers communicating with an outlet leading from the inner chamber, a top plate to cover the inner and outer chambers and provided with an outlet communicating with the flue, a hopper communicating with the chambers, and a

door mounted upon the top plate to normally close the entrance to said hopper.

7. A device of the character described, consisting of an outer chamber having a surrounding side wall and a bottom wall with a large opening therein, an inner chamber communicating with the opening and having a surrounding side wall spaced from the side wall of the outer chamber to leave an intervening flue which communicates with an outlet leading from said inner chamber, and a top plate to cover the inner and outer chambers and provided with an outlet communicating with the intervening flue. 25 30 35

In testimony whereof I affix my signature, in the presence of two witnesses.

FRANK SMITH.
